UNITED STATES PATENT OFFICE.

WARNER HARTUNG, OF BROOKLYN, NEW YORK, ASSIGNOR TO HENRY J. GAISMAN AND FERDINAND S. M. BLUN, OF NEW YORK, N. Y.

WAIST-BELT.

SPECIFICATION forming part of Letters Patent No. 767,941, dated August 16, 1904.

Application filed September 12, 1902. Serial No. 123,082. (No model.)

To all whom it may concern:

Be it known that I, WARNER HARTUNG, a citizen of the United States, and a resident of New York city, borough of Brooklyn, New York, have invented certain new and useful Improvements in Waist-Belts, of which the following is a specification.

My invention relates to improvements in the class of waist-belts that have a plurality of strap-like parts movably connected together, and in carrying out my invention I connect the strap-like parts together by hinge-joints, and the ends of the belt are provided with means for connecting the belt around a waist.

The invention further contemplates the novel details of improvement that will be more fully hereinafter set forth and then pointed out in the claims.

Reference is to be had to the accompanying drawings, forming part hereof, wherein—

Figure 1 is a face view of a waist-belt embodying my invention. Fig. 2 is an enlarged detail view of the hinge-joint between two of the strap-like parts. Fig. 3 is a section on the line 3-3 in Fig. 2 looking in the direction of the arrows. Fig. 3^a is a detail view of the hinge-joint. Fig. 4 is a view similar to Fig. 2, showing means for maintaining the edges of the straps in proper relation at the hinged ends. Fig. 5 is an edge view in section on the line 5-5 in Fig. 4 looking in the direction of the arrows. Fig. 6 is a view similar to Fig. 2, showing a modified arrangement of the hinge connecting the strap-like parts; and Fig. 7 is a section on the line 7-7 in Fig. 6 looking in the direction of the arrows.

Similar numerals of reference indicate corresponding parts in the several views.

In the drawings the numerals 1 2 3 indicate the main or strap-like parts of a waist-belt, which are connected together at their adjacent ends by hinges.

In Figs. 1 to 5, inclusive, the tongues or members 1^a 2^a 3^a of the hinges are made integral with the strap-like parts 1 2 3, respectively, by properly cutting the straps and folding the tongues back upon the straps and

securing them thereto, as by stitches, to form eyes, as 1^b, to receive the pin 4. (See Fig. 3.) 50

As shown in Fig. 3^a, I cut slots or openings 1^c near the end of the strap and fold the end part 1^a back upon the straps to form the tongues and eyes for the pin 4. As shown, the strap-like parts are connected together 55 by intermeshing the several tongues at the adjacent ends of the straps and passing the pins 4 through the eyes.

As shown in the drawings, tongues 1^a 2^a 3^a are located at one corner of a strap; but at 60 the adjacent corner of the same strap there is no tongue, so that when the straps are made of such pliable material as leather considerable play may take place between such end of the strap and the adjacent tongue of the 65 next strap. To reduce such liability, I have shown in Figs. 4, and 5 a rigid or non-elastic connection between the end of the strap and the pin 4, and the arrangement shown consists of a wire 5, coiled around the pin 4 and firmly 70 connected to the adjacent strap. (See Figs. 4 and 5.) The wire 5 is shown bent toward the strap and passed between the lapping or folded parts that form the part of the hinge-joint, and the wire may be secured in place by 75 the stitches 6, that hold the parts together at the hinge, or otherwise. The eye of the coil of wire 5 may swing on the pin 4, and the wire 5 serves to hold the adjacent edge of the strap in proper alignment with the pin 4. 80

Instead of having the tongues of the hinges made integral with the straps 1 2 3, the hinges may be made separately, as shown at 7 in Figs. 6 and 7, and secured to the adjacent ends of the straps 1 2 3, as by stitches or the 85 like, and when such hinges are made of pliable material, such as leather, the wire connections 5 may also be utilized.

The belt constructed as described is provided with means for connecting its ends together 90 around a waist, such as a buckle 8 at one end of the belt and holes at the opposite end, or in any other well-known manner.

The belt described will be found desirable in that the hinge-joint provides a strong connection between the strap-like parts and per-

mits the belt to adjust itself properly in position around a waist, and the device is also simple to manufacture and strong in use.

While I have shown three strap-like parts 5 composing the main portions of the belt, it is evident that one or more strap-like parts may be used and connected together as described.

Having now described my invention, what I claim is—

- 10 1. A waist-belt comprising a plurality of strap-like parts provided with tongues made integral therewith at adjacent ends, forming eyes, the tongues at adjacent ends of the straps being intermeshed and their eyes alined, a pin passing through said eyes and connecting adjacent tongues together, and means for connecting the ends of the belt together around a waist, substantially as described.
- 15 2. A waist-belt comprising a plurality of strap-like parts provided near their adjacent ends with slots providing tongues, the material of the straps beyond the slots being

folded backwardly upon itself forming eyes, the tongues being intermeshed and the eyes alined, a pin connecting the corresponding 25 eyes of adjacent straps together, and means for connecting the ends of the belt together around a waist, substantially as described.

3. A waist-belt comprising a plurality of strap-like parts connected together by a hinge- 30 joint, and a non-elastic connection between the hinge and the adjacent edge of a strap-like part, substantially as described.

4. A waist-belt comprising a plurality of strap-like parts connected together by a hinge- 35 joint, and a wire having one end connected with the pin of the hinge and the other end connected with the adjacent end of a strap, substantially as described.

WARNER HARTUNG.
